UNITED STATES PATENT OFFICE.

FREDERICK J. SCUDDER, OF LONG ISLAND, NEW YORK, ASSIGNOR TO WESTERN ELECTRIC COMPANY, INCORPORATED, OF NEW YORK, N. Y., A CORPORATION OF NEW YORK.

AUTOMATIC TELEPHONE-EXCHANGE SYSTEM.

Application filed June 23, 1921. Serial No. 479,730.

To all whom it may concern:

Be it known that I, FREDERICK J. SCUDDER, a citizen of the United States, residing at Long Island, in the county of Queens, 5 State of New York, have invented certain new and useful Improvements in Automatic Telephone-Exchange Systems, of which the following is a full, clear, concise, and exact description.

10 This invention relates to automatic telephone exchange systems, and more particularly to automatic systems in which the selective movements of the various switches are controlled by a central office sending device.

15 It is the object of this invention to provide an improved method of controlling the release of the selector switches, and the associated sending device.

20 It is more definitely the object of the invention to provide means, such that release of the connection will take place properly in case the call is abandoned before the called subscriber has responded, and regardless of 25 the stage of operation to which the connection has progressed at the time of such abandonment.

25 It is a further object of the invention to reduce the time interval before a calling subscriber may initiate a second call after abandoning a previous call.

30 In systems employing a central office sender various problems arise under the various conditions of premature abandonment of calls. If a call is abandoned before the first numerical switch has been positioned, it is possible to immediately restore the sending device. If the first numerical switch has been positioned it is usually necessary to operate all the succeeding switches in the train before release takes place, since otherwise the progression switch in the sender might be left in a position from which it could not be advanced, which would put the sender 40 out of service until the condition was eliminated. Under certain conditions, difficulties would also be encountered in releasing succeeding switches in the train.

45 A feature of the invention is the provision of means such that the release of the connection is controlled by the condition of the sending device, that is, if connection has not proceeded far enough to prevent proper

restoration of the sender, this fact will be indicated and allow disconnection to proceed. If connection has advanced to a point where it will be necessary to fully actuate the sender, the abandonment of the call is made ineffective to cause release until all the switches have been operated whereupon release will take place immediately. 55 60

A further feature of the invention is the use of a release control relay which is at certain times under the control of the sender, and at other times under the control of the calling subscriber or operator who has initiated the call. 65

It is thought that the invention will best be understood from the following detailed description, reference being had to the accompanying drawings. 70

In the drawings, Fig. 1 shows the circuit of an individual line switch for extending a calling line to an idle district selector; Fig. 2 shows the circuits of a district selector switch and a sender selector switch; Fig. 3 shows circuits for the sender controlling sequence switches and a step-by-step progression switch. The sequence switch contacts above and to the right of the broken line in this figure are controlled by sequence switch 400, while the sequence switch contacts below and to the left of the broken line are controlled by sequence switch 301; Fig. 4 shows the registering devices which control the action of the counting relays of Fig. 3. 75 80 85

The circuits have been simplified as far as possible in order to eliminate matter which is not necessary to an understanding 90 of the invention. The invention has been applied to a system of the type shown and described in an application Serial No. 487,520, filed July 25, 1921, in the name of Alben E. Lundell. The application just 95 mentioned shows in detail the complete circuits and describes the complete operation of a sending device similar to the one shown in Figs. 3 and 4 of the present application. The translator switch shown in Fig. 4 is a 100 step-by-step two-motion switch and responds directly to the first two series of impulses. This translator switch therefore, corresponds to the first two registers and translator switch of the above mentioned Lundell 105 application taken in combination.

The detailed operation of the system is as follows: When a subscriber at substation 1 removes his receiver from the switchhook a circuit is completed from grounded 5 battery, right-hand winding of line relay 2, inner lower armature and back contact of cut-off relay 3, through the loop of the calling substation line, upper armature and back contact of relay 3 to ground. Line 10 relay 2 is energized in this circuit and attracts its armatures. Test brush 5 is at this time in engagement with its normal contact, not shown, and since its normal contact is connected to ground, the energization of line 15 relay 2 completes a circuit from grounded battery, winding, armature and back contact of stepping magnet 4, lower armature and back contact of cut-off relay 3, right-hand armature and front contact of line relay 2, conductor 15, test brush 5, normal terminal to ground. Magnet 4 is energized and interrupts its own circuit to release its armature and advance the line switch into its first off normal position. As soon as the 20 line switch makes its first step, off-normal contact 13 closes and off-normal spring 14 releases its upper contact and engages its lower contact. Off-normal contact 14 removes the control of the cut-off relay 25 from any line which may be calling and supplies battery to test terminal 16, to render the calling line busy to other calling subscribers.

Test terminals of trunks extending to 35 busy district circuits will be characterized by the presence of ground potential on such test terminals as will be evident from the following description. As long as test brush 5 engages contacts associated with 40 busy trunks, ground will be supplied to conductor 15, and stepping magnet 4 will continue to interrupt its own circuit to cause the advance of the line switch. As soon as test brush 5 engages a terminal on which 45 there is no ground potential the circuit for magnet 4 is opened and the switch is brought to rest with its brushes resting on the terminal set of an idle trunk leading to an available district selector.

50 It should be noted that during the operation of the line switch a circuit for cut-off relay 3 is in existence. This circuit extends from ground, upper and lower windings of cut-off relay 3, left-hand winding of line 55 relay 2, left-hand armature and front contact of relay 2, and thence to grounded battery, through the winding of magnet 4. Cut-off relay 3 cannot however, be energized in this circuit, since its windings are 60 short-circuited by the direct ground supplied to conductor 15 by way of test terminals 9. As soon as the brush set comes to rest on the selected terminal set a circuit is completed from grounded battery, resistance 65 199 (Fig. 2), contacts of sequence

switch spring 198, armature and back contact of relay 102, conductor 106, terminal 9, test brush 5, conductor 15, left-hand winding, armature and front contact of relay 2, through the windings of cut-off relay 3 to 70 ground. The presence of battery potential at terminal 9 short-circuits magnet 4 and allows cut-off relay 3 to operate. The operation of cut-off relay 3 causes the deenergization of line relay 2. 75

A circuit is now completed from grounded battery, (Fig. 2), right-hand winding of relay 102, armature and back contact of relay 139, lower right-hand contact of sequence switch spring 103, sleeve conductor 80 104, terminal 11, brush 7, winding of message register magnet 17, lower middle armature and front contact of relay 3, lower winding of relay 3 to ground. Relay 102 is energized, and at its inner left-hand armature and front contact supplies ground by way of conductor 105 to test conductor 106 and its associated test contacts, to render the trunk non-selectable to other hunting line switches. The energization of relay 102 85 also completes a circuit from grounded battery, right-hand winding of relay 107, upper left-hand contact of sequence switch spring 108, lower contacts of sequence switch spring 109, right-hand armature and front 90 contact of relay 102 to ground. Relay 107 is energized in this circuit. 95

Assuming that the sender, on the terminals of which the brushes of the sender selector are resting, is busy, and that this 100 busy condition is indicated by presence of ground on the test terminal of such sender, a locking circuit for relay 107 is completed from grounded battery, left-hand winding and left-hand armature and front contact 105 of relay 107, conductors 110 and 111, upper left-hand contact of sequence switch spring 112, lower left-hand contact of sequence switch spring 113, conductor 114, test brush 115 and its associated test terminal to 110 ground. Relay 107 completes a circuit from grounded battery, power magnet of sequence switch 100, lower right-hand contact of sequence switch spring 116, inner right-hand armature and front contact of relay 107, 115 lower left-hand contact of sequence switch spring 117 to ground for moving this sequence switch out of position 1 and into position 2, under the control of its master spring contact 101. 120

In position 2 of sequence switch 100 a circuit is completed for causing the selection of an idle sender. The circuit for the sender selector stepping magnet 118 extends from grounded battery, armature and back contact of magnet 118, winding of magnet 118, conductor 119, lower contact of sequence switch spring 120, inner right-hand armature and front contact of relay 107, and the lower contact of sequence switch spring 130

117 to ground. Stepping magnet 118 interrupts its own circuit and causes the advance of the sender selector brushes until an idle sender is found. When an idle 5 sender is found the absence of ground on the test terminal of such sender breaks the locking circuit of relay 107 and this relay deenergizes, and opens the circuit of stepping magnet 118, thus bringing the sender 10 selector to rest. Relay 107 upon deenergization also completes a circuit from grounded battery, power magnet of sequence switch 100, upper right-hand contact of sequence switch 116, inner right-hand armature and 15 back contact of relay 107, lower contact of sequence switch spring 117 to ground, for moving this sequence switch out of position 2 and into position 3.

During the hunting movement of the 20 sender selector a circuit is in existence from grounded battery, armature and back contact of stepping magnet 118, winding of magnet 118, winding of relay 121, lower right contact of sequence switch spring 122 25 to ground. The presence of direct ground on conductor 119 shunts relay 121 at this time, to prevent its operation. However, as soon as relay 107 is deenergized this shunt is removed and relay 121 is energized to 30 connect the controlling leads to the selected sender. Relay 121 at its inner left-hand armature supplies ground to the terminal associated with test brush 115 to render the 35 sender non-selectable by other sender selectors.

As soon as the sender has been seized and relay 121 has operated, a circuit is completed from grounded battery, winding of line relay 215 (Fig. 3), conductor 216, brush 123, outer left-hand armature and front contact 40 of relay 121, upper left-hand contact of sequence switch spring 125, trunk conductor 126, terminal 12, brush 8, inner lower armature of cut-off relay 3, through the substation apparatus including the sending device, the upper armature and front contact 45 of relay 3, brush 6, terminal 10, trunk conductor 127, upper left-hand contact of sequence switch spring 128, conductor 129, brush 130 and its associated contact, conductor 131 and the right-hand winding of an induction coil 213. Relay 215 is energized in this circuit and completes a circuit for slow-release relay 217. The function of relay 399 will be described hereinafter.

It should be noted that upon the energization of relay 121 a circuit is completed from grounded battery, winding of relay 302 70 (Fig. 3), upper contacts of sequence switch spring 303, sender selector brush 115, conductor 114 to ground at the inner left-hand armature and front contact of relay 121. Relay 302 is energized in this circuit and locks up through its inner right-hand armature, while at its outer right-hand armature it supplies ground to sequence switch 301 by way of the upper left-hand contact of sequence switch spring 308 to advance this sequence switch out of position 1 and into position 3.

It will be assumed that the line to be selected is one which terminates in a full mechanical exchange which may be selected directly by means of a district selector and an office selector. In this case the registers and class register switch will have to be set in such positions as to control brush and group selection at the district, office, and incoming switches, and brush, group and line selection at the final switch.

In order to prevent confusion as to which switches the various brushes and contact arms shown in Figs. 3 and 4 are related, the brushes belonging to the progression or side switch have been indicated by the letters SS; the arms of the register switch which is set in response to the two series of impulses of the office code, have been designated by the letter C; the brushes of the thousands register are indicated by the letters TH, and those of the hundreds, tens and units registers have been designated by the letters H, T, and U respectively.

It will be assumed that when the subscriber operates his dial to transmit the first letter of the office code, three impulses will be sent. The first interruption caused by the return of the dial causes the deenergization of relay 215. Before proceeding with the operation of setting the various register switches it should be noted that the energization of relay 217 completes a circuit from ground through its armature and back contact, right-hand armature and front contact of relay 217, winding of slow-to-release relay 305, brush 312, conductor 325, outer left-hand armature and front contact of relay 217 to ground, for energizing the relay 500.

The deenergization of relay 215 completes a circuit from ground through its armature and back contact, right-hand armature and front contact of relay 217, winding of slow-to-release relay 305, brush 312, conductor 325, 115 right-hand armature and front contact of relay 500, winding of vertical stepping magnet 504 to battery and ground. The retraction of the armature of relay 215 also completes a circuit from grounded battery, 120 conductor 324, right-hand armature and front contact of relay 500, winding of vertical stepping magnet 504 to battery and ground. The retraction of the armature of relay 215 also completes a circuit from grounded battery, 125 conductor 324, right-hand armature and front

through the winding of relay 306, brush 313, conductor 322, outer left-hand armature and front contact of relay 500, contact and armature of magnet 504, and thence to ground at the armature and back contact of relay 215. Relay 306 becomes energized and completes a circuit from ground through its outer armature and contact, winding of relay 305, brush 312, conductor 324, and thence as above traced, through the winding of magnet 504 to battery and ground. Relay 306 is therefore energized in a circuit which depends upon the armature and contact of the vertical stepping magnet 504, and as long as it remains energized a circuit for such magnet is maintained independently of the armature and back contact of relay 215. Should the opening period of the line circuit be abnormally short due to an imperfect dial or for any other reason, the consequent attraction of the armature of relay 215 will not cause the premature opening of the circuit of magnet 504. The magnet 504 remains energized due to the continued energization of the relay 306, until it has had time to advance the brushes of the switch a full step to position them opposite the first level of terminals. When the full step has been completed the armature and contact of magnet 504 are opened and the circuit of relay 306 is interrupted. Relay 306 thereupon releases its armatures and opens the circuit of magnet 504, which in turn becomes de-energized. Relay 306 furthermore maintains a circuit at its inner armature and contact for the slow-to-release relay 217. Relay 217 is designed to remain operated during the normal periods in which this circuit is opened by the armature of relay 215. If, however, relay 215 remains de-energized for an abnormally long period, relay 217 cannot become deenergized, due to the fact that relay 306 provides a substitute holding circuit therefor. As the translator switch, by which term the switch which receives the first two series of impulses to register the office code will be hereinafter designated, takes its first step the contact 531 is opened to interrupt the original energizing circuit of relay 500. Relay 500 however, remains energized in the circuit as follows: grounded battery, through the winding, front contact, and inner left-hand armature of relay 500, conductor 323, contact and armature of slow-to-release relay 305 to ground. Relay 305 does not retract its armature during the brief interruptions of its circuit at the armature and back contact of stepping relay 215. On each of the remaining interruptions of the line circuit in the transmission of the first digit, the brushes 511, 512, 513, 514, 515 and 516 of the translator are advanced one step until they are finally positioned opposite the third level of ter-

minals in their respective banks. Following the third impulse the stepping relay 215 remains energized for a comparatively long period, during which interval the slow-to-release relay 305 is permitted to release its armature. Relay 305 opens the holding circuit of relay 500, which becomes deenergized.

The calling subscriber next operates the sending dial to transmit the second series of impulses representing the second digit of the office code. It will be assumed that seven impulses are sent. On the first opening of the impulse circuit relay 215 becomes deenergized and completes a circuit to ground through its armature and back contact, right-hand armature and front contact of relay 217, winding of relay 305, brush 312 and its normal contact, conductor 324, right-hand armature and back contact of relay 500, winding of the rotary stepping magnet 503 to battery and ground. A circuit is also completed for the energization of relay 306 as follows: grounded battery, winding of said relay, brush 313 and its normal contact, conductor 322, left-hand normal contact of relay 500, contact and armature of stepping magnet 503 and thence to ground as above traced, at the back contact and armature of relay 215. Relay 306 in a manner similar to that previously described closes a circuit for the rotary stepping magnet 503 to insure that said magnet takes a full step before its circuit is opened. For each of the seven impulses of the second digit the brushes of the translator switch are advanced one step over the third level of terminals, and are finally brought to rest in engagement with the seventh set of terminals in such level. The slow-to-release relay 305, which became energized during the transmission of the second series of impulses, completes a circuit from ground, through its armature and contact, conductor 323, inner left-hand armature and back contact of relay 500, conductor 327, winding of progression switch magnet 316, to battery and ground. Magnet 316 energizes preparatory to advancing the brushes of the control switch when its circuit is opened. After the last impulse has been transmitted relay 215 remains energized for a period of time sufficient to permit the release of slow relay 305. Relay 305 opens the circuit of stepping magnet 316 which in turn deenergizes and advances the brushes 311, 312, 313, 314, and 315 into engagement with their second position terminals. The two movement step-by-step translator switch has thus been positioned in accordance with the office code to determine the operation of the district and office switches to route the call in the proper direction. The calling subscriber now continues to manipulate his dial to transmit the digits corresponding to the nu-

merical designation of the wanted line. In a ten thousand line office the subscriber's line number consists of four digits and consequently, four numerical registers 540, 545, 550 and 555 are provided to take a record of these digits. When the dial is operated to transmit the first digit of the wanted number, relay 215 becomes deenergized and completes a circuit from ground, through its 5 armature and back contact, right-hand armature and front contact of relay 217, brush 312, and its second terminal, conductor 329, winding of stepping magnet 541, to battery and ground. Magnet 541 energizes and 10 when its circuit is broken at the end of the first impulse advances the brushes 542, 543 etc., into engagement with the second position terminals. In a similar manner for each succeeding impulse the brushes of register 540 are advanced step-by-step until a 15 position corresponding to the first digit is reached. Relay 305 completes the circuit above traced for stepping magnet 316 and at the end of the series of impulses this 20 relay releases to permit the deenergization of such magnet. The brushes of the control switch are thereupon advanced into engagement with their third position terminals. 25

The first deenergization of relay 215 in 30 response to the transmission of the second series of impulses of the wanted line number causes a circuit to be closed from ground through the armature and front contact of relay 217, winding of relay 305, brush 312 35 and its third terminal, conductor 330, winding of stepping magnet 546 of the hundreds register, to battery and ground. The register 545 is thereupon moved forward step-by-step in response to the second series of 40 impulses. Relay 305 closes the above traced circuit for the stepping magnet 316 and at the end of the series opens its circuit to advance the control switch to its fourth position. 45

In a similar manner the remaining series of impulses are directed to the stepping magnets 551 and 556, of the registers 550 and 555 respectively, and these registers are advanced into their proper positions. Following 50 the transmission of the last series of impulses the control switch is advanced to its sixth position.

The circuits of the system are arranged to start the district and office selections immediately after the setting of the translator switch, or in other words, as soon as the record of the called office has been received. While the district and office switches are being positioned the subscriber may continue the dialing operation to register the 55 number of the called line.

Immediately after the translator switch has been positioned the control switch is moved to its second position terminal as explained. A circuit is then completed from

grounded battery, winding of relay 307, brush 314 and its associated terminal to ground. Relay 307 becomes energized and locks up in a circuit extending through its left-hand armature and front contact to ground by way of the sequence switch spring 398. Relay 307 at its inner armature completes a circuit from grounded battery, power magnet of sequence switch 301, lower right-hand contact of sequence switch spring 308, left-hand armature and back contact of relay 371 to ground for causing the advance of class sequence switch 301 into a position to properly route the call. The position taken by sequence switch 301 is determined 70 in accordance with the position which has been assumed by the translator switch. Class sequence switch 301 continues in motion until relay 371 is energized. The control of the energizing circuit of relay 371 75 is successively shifted to the various terminals in the translator bank served by translator brush 511 by way of the contacts of sequence switch springs 372 and 373. When sequence switch 301 reaches position 80 9 $\frac{1}{2}$ a circuit is completed from grounded battery, winding of relay 371, upper right-hand contact of sequence switch spring 372, conductor 376, terminal 522, translator brush 511 to ground. Relay 371 is energized and opens at its left-hand armature, the driving circuit of sequence switch 301 which advances into position 10 under the control of its master contact and comes to rest in this position. Relay 371 upon energization locks by way of its right-hand armature, and the lower contact of sequence switch spring 398. Relay 371 at its left-hand armature completes a circuit from grounded battery, power magnet of sequence switch 400, upper contact of sequence switch spring 439, left-hand armature and front contact of relay 371, inner armature and front contact of relay 307 to ground for moving this sequence switch out of position 95 100 105 110 115 120 125 130 135 140 145 150 155 160 165 170 175 180 185 190 195 inner right-hand armature and front contact of relay 107, lower contact of sequence switch spring 117 to ground for moving sequence switch 100 out of position 3 and into position 4. Relay 107 remains energized in position 4 of sequence switch 100 due to the closure of a locking circuit extending from grounded battery, left-hand winding, armature and front contact of relay 107, conductors 110, 111, upper left-hand contact of sequence switch spring 112 to ground over the path described.

In position 4 of sequence switch 100 a circuit is completed for up-drive magnet 124. This circuit extends from grounded battery, winding of magnet 124, upper right-hand contact of sequence switch spring 120, inner right-hand armature and front contact of relay 107, lower contact of sequence switch spring 117 to ground. The energization of magnet 124 causes the district selector to advance its brush shaft in a brush selecting movement.

Referring now to Fig. 3 it will be observed that the energization of stepping relay 445 completes a circuit from ground, armature and front contact of relay 445, upper contact of sequence switch spring 465, conductor 469, translator brush 512, terminal 523, and thence to the armature and back contact of the No. 2' counting relay (Fig. 3), and the winding of the No. 2 counting relay to grounded battery. The No. 2 counting relay is energized in this circuit and prepares in the well-known manner the circuit for the No. 2' counting relay. The winding of the No. 2' counting relay is however, shunted by the ground controlled at the armature and front contact of relay 445, and does not energize at this time.

As soon as the district brush shaft is advanced a sufficient distance to allow the commutator brush 135 to engage the first conducting segment of commutator 136, stepping relay 445 is shunted down, since the locking circuit of relay 107 now extends from grounded battery, left-hand winding of relay 107, left-hand armature and front contact of relay 107, conductors 110, 111, upper left-hand contact of sequence switch spring 112, upper right-hand contact of sequence switch spring 113, commutator 136, and commutator brush 135 to ground. The shunting of stepping relay 445 causes it to deenergize and allow the No. 2' counting relay to be energized. The energization of the No. 2' counting relay prepares a circuit for the No. 1 counting relay in the well-known manner. When brush 135 leaves the conducting segment of commutator 136, the shunt is removed from stepping relay 445, and this relay again energizes, and causes the energization of the No. 1 counting relay. The counting relays are successively actuated until the third shunting down of the step-

ping relay allows the energization of the No. 0' counting relay and the relay 446 in parallel. The circuit of these relays extends to ground by way of the armature and front contact of the No. 0 counting relay, and the lower contact of sequence switch spring 463. The energization of the No. 0' counting relay completes a circuit from grounded battery, winding of the power magnet of sequence switch 400, upper contact of sequence switch spring 441, armature and front contact of the No. 0' counting relay to ground for moving this sequence switch out of position 2 and into position 4.

The energization of relay 446 opens the lower branch of the locking circuit of relay 107 and when, a moment later, brush 135 engages an insulating segment of commutator 136, the circuit of relay 107 is broken and this relay deenergizes, completing a circuit from grounded battery, power magnet of sequence switch 100, upper right-hand contact of sequence switch spring 116, inner right-hand armature and back contact of relay 107, lower contact of sequence switch spring 117 to ground, for moving sequence switch 100 out of position 4 and into position 5. The deenergization of relay 107 also opens the circuit of up-drive magnet 124 and brings the selector to rest in a position to trip the third set of brushes. As soon as sequence switch 400 leaves position 2 the locking circuits of the counting relays are broken at the upper and lower right-hand contacts of sequence switch spring 463 and the counting relays are restored.

In position 5 of sequence switch 100 the fundamental circuit is again completed, from grounded battery, left-hand winding of line relay 107, lower left-hand and upper right-hand contacts of sequence switch spring 112, inner right-hand armature and front contact of relay 121, brush 132 and its associated contact, conductor 133, contacts of sequence switch springs 347 and 443, winding of stepping magnet 445, armature and back contact of relay 446, contact of sequence switch spring 444 to ground. Relays 107 and 445 are energized in this circuit, relay 107 completing a locking circuit for itself by way of its left-hand armature and front contact, conductors 110 and 111, and the upper left-hand contact of sequence switch spring 112 to ground over the path described. Relay 107 also completes a circuit from grounded battery, power magnet of sequence switch 100, lower right-hand contact of sequence switch spring 116, inner right-hand armature and front contact of relay 107, lower contact of sequence switch spring 117 to ground, for moving sequence switch 100 out of position 5 and into position 6.

In position 5 of sequence switch 100 a circuit was completed from grounded battery,

winding of trip magnet 137, upper right-hand contact of sequence switch spring 122 to ground. The trip magnet was energized in this circuit to operate the trip rod so that 5 on subsequent upward movement of the brush shaft the third set of brushes will be released into engagement with the section of the contact bank served by it.

The above mentioned energization of stepping relay 445 completes a circuit from ground, armature and front contact of relay 445, lower contact of sequence switch spring 465, conductor 470, translator brush 513, terminal 524, and thence through the armature and back contact of the No. 9' counting relay (Fig. 3), and the winding of the No. 9 counting relay to grounded battery. The No. 9 counting relay is energized and prepares a circuit for the No. 9' counting relay.

20 In position 6 of sequence switch 100 a circuit is again completed for up-drive magnet 124, extending from grounded battery, winding of magnet 124, upper right-hand contact of sequence switch spring 120, inner right-hand armature and front contact of relay 107, lower contact of sequence switch spring 117 to ground. Under the control of magnet 124, the selector brush shaft is moved upwardly to select the desired group. As soon 25 as commutator brush 137 engages a conducting portion of commutator 138, stepping relay 445 is shunted down and deenergizes to allow the energization of counting relay No. 9'.

35 On the tenth shunting down of stepping relay 445, counting relay No. 0' is energized in parallel with relay 446 in a manner similar to that previously described. The energization of relay 446 opens the 40 lower branch of the locking circuit of relay 107 and when, a moment later, brush 137 engages an insulating segment of commutator 138, the locking circuit of relay 107 is broken and this relay deenergizes. The de- 45 energization of relay 107 completes a circuit from grounded battery, power magnet of sequence switch 100, upper right-hand contact of sequence switch spring 116, inner right-hand armature and back contact of 50 relay 107, lower contact of sequence switch spring 117 to ground for moving sequence switch 100 out of position 6 and into position 7. The deenergization of relay 107 also opens the circuit of up-drive magnet 124 and brings the selector to rest.

55 The energization of the No. 0' counting relay completes a circuit to advance the sender sequence switch 400 out of position 4 and into position 6, in a manner identical with that previously described.

With sequence switch 100 in position 7 a circuit is completed from grounded battery, right-hand winding of relay 107, upper left-hand contact of sequence switch spring 108, lower contacts of sequence switch spring

109, right-hand armature and front contact of relay 102 to ground. Relay 107 is energized in this circuit.

It should be observed at this point that when sequence switch 100 reached position 2, a circuit was completed from grounded battery, left-hand winding of relay 139, upper left-hand contact of sequence switch spring 122 to ground at spring 166. Relay 139 was energized in this circuit and at its 70 left-hand armature transferred the holding circuit of relay 102 from the lower right-hand contact of sequence switch spring 103 to the upper right-hand contact of such sequence switch spring. Relay 139 remains 75 energized over this circuit until sequence switch 100 leaves position 11 except in the case of an abandoned call, which condition 80 will be described in detail hereinafter.

With relays 107 and 139 energized in position 7 of sequence switch 100, a circuit is completed from grounded battery power magnet of sequence switch 100, lower right-hand contact of sequence switch spring 116, inner right-hand armature and front contact of relay 107, right-hand contact of sequence switch spring 117, right-hand armature and front contact of relay 139 to ground for moving sequence switch 100 out of position 7 and into position 8. As soon 90 as sequence switch 100 reaches position 7½ a locking circuit for relay 107 is completed, extending from grounded battery, left-hand winding of relay 107, left-hand armature and front contact of relay 107, conductor 110, lower left-hand and upper right-hand contacts of sequence switch spring 145 to test brush 146 and its associated contact, and thence to ground, provided the associated trunk is busy. It will be assumed that 95 the first trunk in the group is busy. Relay 107 therefore, remains energized and completes a circuit from grounded battery, winding of up-drive magnet 124, upper right-hand contact of sequence switch spring 120, inner right-hand armature and front contact of relay 107, lower left-hand contact of sequence switch spring 117 to ground. The selector brush set is now 100 moved upwardly over the terminals in the selected group and when an idle trunk is 105 encountered, ground will no longer be found on the terminal associated with test brush 146. This branch of the locking circuit of relay 107 is therefore, opened, but 110 the relay is held energized an instant longer in order to properly center the brush set due to the closure of a circuit extending from grounded battery, right-hand winding of relay 107, upper right-hand contact 115 of sequence switch spring 108, a conducting portion of commutator 149, commutator brush 180 to ground. As soon as commutator brush 180 engages an insulating segment of commutator 149, at which time the 120

125 130

brushes will be accurately centered on the selected terminal set, all branches of the holding circuits of relay 107 are opened, and this relay deenergizes, causing in turn the deenergization of up-drive magnet 124, and bringing the selector to rest. The district selector has now been actuated to seize a trunk leading to an idle office selector switch. The deenergization of relay 107 also completes a circuit from grounded battery, power magnet of sequence switch 100, upper right-hand contact of sequence switch spring 116, inner right-hand armature and back contact of relay 107, lower left-hand contact of sequence switch spring 117 to ground, for moving this sequence switch out of position 8 and into position 9.

When sequence switch 100 reached position 4, and with sequence switch 400 in position 4 or some position beyond, a circuit was completed from grounded battery, winding of charge relay 152, lower contact of sequence switch spring 140, conductor 141, outer right-hand armature and front contact of relay 121, lower right-hand contact of sequence switch spring 142, brush 143 and its associated contact, conductor 144, resistance 223, contact of sequence switch spring 499, armature and back contact of relay 498 to ground. Relay 152 was energized in this circuit and remains energized until sequence switch 100 leaves position 10.

As soon therefore, as sequence switch 100 reaches position 9 a circuit is completed from grounded battery, right-hand winding of relay 107, upper left-hand contact of sequence switch spring 108, lower right-hand and upper left-hand contacts of sequence switch spring 109, right-hand armature and front contact of relay 152 to ground. Relay 107 is energized and completes a circuit from grounded battery, power magnet of sequence switch 100, lower right-hand contact of sequence switch spring 116, inner right-hand armature and front contact of relay 107, lower left-hand contact of sequence switch spring 117 to ground for moving sequence switch 100 out of position 9 and into position 10. In position 10, relay 107 remains energized over the circuit previously described. It is to be observed that the trunk leading to the selected office selector switch is made busy against other hunting district selector switches as soon as sequence switch 100 reaches position 8½, since ground is supplied to test terminal 153 by way of the upper contacts of sequence switch spring 145.

In position 10 of sequence switch 100, the fundamental circuit is extended to the office selector switch (not shown) by way of the lower contacts of sequence switch spring 151 and the upper left-hand and lower right-hand contacts of sequence switch spring 155 by way of brushes 154 and 157 and their associated terminals 159 and 158. The fun-

damental circuit is entirely metallic to the office selector and the switches beyond, and extends from the stepping relay 445 by way of the contact of sequence switch spring 466, conductor 343, sender selector brush and its 70 associated contact to the ring conductor of the trunk as described. It has not been considered necessary to disclose the circuits of the office, incoming, and final selector switches, since they are fully disclosed in 75 the previously mentioned Lundell application, Serial No. 487,520. In case the call was to have been extended directly to an incoming switch the class sequence switch would have been in a position to cause the 80 advance of the sender sequence switch 400 through positions 6 and 8.

The necessary selecting operations are performed at the succeeding switches in the well-known manner, under the control of 85 the counting relays and the registers shown in Fig. 4. At the conclusion of each selective operation, the energization of the 0' counting relay operates to advance sequence switch 400 into position to control the next 90 selection, and during such advance of the sequence switch the counting relays are restored. It has been assumed in order to simplify the disclosure, that office brush selection takes place in position 6 of sequence switch 400, office group selection in position 8, incoming brush selection in position 10, incoming group selection in position 12, final brush selection in position 14, final group 95 selection in position 16, and final line selection in position 17. At the conclusion of the selective operations, the sender selector switch 400 is, therefore, in position 18.

When sequence switch 400 reaches position 18 a circuit for relay 498 is completed, by 105 way of the contact of sequence switch spring 497. The energization of relay 498 opens the circuit which has been holding relay 152 (Fig. 2), energized, and relay 152 is deenergized. Relay 152 opens the holding circuit through the right-hand winding of relay 107, and relay 107 is deenergized and completes a circuit from grounded battery, power magnet of sequence switch 100, upper right-hand contact of sequence switch spring 116, inner right-hand armature and back contact 110 of relay 107, and the lower contact of sequence switch spring 117 to ground, for moving this sequence switch out of position 10 and into position 13, which is the talking position.

As soon as sequence switch 100 leaves position 10½ the impulse circuit into the sender is opened at the upper left-hand contacts 115 of sequence switch springs 128 and 125, respectively. As a result of the opening of the impulse circuit, relay 215 is deenergized, causing in turn the deenergization of slow-to-release relays 217 and 399.

A circuit is now completed from grounded 130

battery, winding of control switch stepping magnet 316, armature and back contact of such magnet, brush 311 and its sixth contact, and the right-hand armatures and back contacts of relays 217 and 215 to ground. Magnet 316 interrupts its own circuit and advances the control switch into its tenth position, in which position its circuit is opened by the advance of brush 311.

10 With the control switch in its tenth position, circuits are completed for restoring the numerical registers. The circuit of the stepping magnet of the thousands register extends from grounded battery, winding of 75 the magnet 541, armature and back contact of such magnet, register brush 542, and an off-normal contact, conductor 579, brush 314 and its tenth contact to ground. In parallel with this circuit, circuits are completed 80 for stepping magnets 546, 551, and 556, by way of the hundreds, tens and units register brushes 547, 552, and 557 respectively. The numerical registers are restored to their 85 normal positions, and when they reach their normal positions, a circuit is completed from 90 grounded battery, winding of control switch stepping magnet 316, armature and back contact of such magnet, control switch arm 315 and its tenth terminal, and thence 95 through brushes 543, 548, 553, and 558 and their normal contacts, to ground. Magnet 316 is energized in this circuit and interrupts its circuit to advance the control switch into its normal position.

35 The step-by-step office code register switch is restored as soon as relays 215 and 217 are deenergized. This is accomplished due to the closure of a circuit from grounded 100 battery, winding of release magnet 502, vertical off-normal contact 532, and thence to ground at the back contact of relay 215. The operation of release magnet 502 restores the two-movement step-by-step register switch in the well-known manner.

45 As soon as the control switch reaches its normal position, a circuit is completed from grounded battery, winding of the power magnet of sequence switch 400, left-hand contact of sequence switch spring 439, control switch arm 311, and its normal contact, and the right-hand armatures and back contacts of relays 217 and 215 to ground. Sequence switch 400 is advanced into position 1.

55 When sequence switch 400 reaches position 1, a circuit is completed for restoring the class sequence switch 301 to its normal position. This circuit extends from 105 grounded battery, power magnet of sequence switch 301, upper right-hand contact of sequence switch spring 308, contact of sequence switch spring 442, control switch brush 311 and its normal contact, and thence to ground as described.

65 The advance of sequence switch 100 into

position 13 causes circuit changes at the succeeding switches in the train to cause ringing current to be applied to the called line, and to cause the sequence switches associated with the remaining switches in the 70 train to be advanced into their various talking positions. The manner in which this is accomplished is well understood in the art. When the called subscriber answers, polarized relay 160 is energized due to the application of a source of battery of suitable polarity to the tip and ring conductors. The energization of relay 160 completes a circuit from grounded battery, winding of 75 charge relay 152, right-hand contacts of sequence switch spring 109, the armature and front contact of relay 160, and the upper right-hand contact of sequence switch spring 166 to ground. Relay 152 upon energization locks up by way of the upper left-hand contact of sequence switch spring 109, and the right-hand armature and front contact of said relay. In position 13 of sequence switch 100, talking battery is supplied to the calling subscriber through the 80 left-hand windings of repeating coil 162 and a relay 167, by way of the lower right-hand contacts of sequence switch springs 125 and 128, respectively.

It would be well to observe at this point 95 that relay 139 is a differentially wound relay, and is maintained energized in positions 2 to 11 of sequence switch 100 by a circuit from grounded battery, left-hand 100 winding of relay 139, upper left-hand contact of sequence switch spring 122 to ground. In positions 1 to 10 of sequence switch 100 a circuit is in existence through the right-hand winding of relay 139, upper 105 left-hand contact of sequence switch spring 140, outer right-hand armature and front contact of relay 121, lower contact of sequence switch spring 142, brush 143 and its associated contact, conductor 144, resistance 145 223, contact of sequence switch spring 499, 110 and the armature and back contact of relay 498, to ground. Since this circuit includes a resistance 223 (Fig. 3), the magnetic flux set up by the right-hand winding of relay 139 is not sufficient to overcome the 115 oppositely poled flux set up in the left-hand winding, and therefore, relay 139 remains energized. When sequence switch 100 reaches position 10½ supervisory relay 167 120 is energized, and the holding circuit of relay 139 now extends through its left-hand winding, armature and front contact of relay 167, and right-hand armature and front contact of relay 139 to ground. As soon as sequence switch 100 leaves position 11 the 125 control of relay 139 is entirely dependent on relay 167.

When conversation is completed and connection is no longer desired, the calling subscriber will replace his receiver causing the 130

deenergization of relay 167, which causes in turn the deenergization of relay 139. A circuit is thereupon completed from grounded battery, power magnet of sequence switch 100, conductor 168, lower right-hand and upper left-hand contacts of sequence switch spring 169, right-hand armature and back contact of relay 139 to ground, for moving sequence switch 100 out of position 12 and into position 17. The deenergization of relay 139 does not allow relay 102 to deenergize since this relay is maintained energized in a holding circuit through its right-hand winding by way of conductor 170, left-hand armature and front contact of relay 152, conductor 171, upper left-hand contact of sequence switch spring 103 to ground through the cut-off relay and message register of the calling subscriber's line.

In position 17 of sequence switch 100, due to the energized condition of charge relay 152, a circuit is completed from grounded battery, right-hand contacts of sequence switch spring 172, outer left-hand armature and front contact of relay 102, left-hand non-inductive winding of relay 102, conductor 170 to ground, over the path described. The battery now supplied through the two windings of relay 102 in parallel raises the potential on conductor 171 sufficiently to allow the message register magnet 17 to operate to record a call against the calling subscriber. It is obvious that if the called subscriber had not answered, charge relay 152 would not have operated and no charge would have been made against the calling subscriber. In this case, relay 102 would have deenergized as soon as relay 139 released, thus causing the immediate release of the calling subscriber's individual line switch as will be described. In position 17 of sequence switch 100, a time interval is provided by means of interrupters indicated at 173 and 174, to insure the allowance of enough time for the proper operation of the register operating magnet. As soon as a circuit is completed through the conducting segments of interrupter 173, a circuit is completed from grounded battery, right-hand winding of relay 107, lower left-hand contact of sequence switch spring 108, conducting segments of interrupter 173 to ground. Relay 107 is energized in this circuit and locks up through its left-hand armature to ground by way of conductors 110, and 111, and the left-hand contacts of sequence switch spring 145. When, shortly thereafter, interrupter 174 closes its contacts, a circuit is completed from grounded battery, left-hand winding of relay 139, conductor 175, upper contacts of sequence switch spring 142, outer right-hand armature and front contact of relay 107, conductor 176, right-hand contacts of se-

quence switch spring 177, contacts of interrupter 174 to ground. Relay 139 is energized in this circuit and completes a circuit from grounded battery, power magnet of sequence switch 100, lower right-hand contact of sequence switch spring 116, inner right-hand armature and front contacts of relay 107, upper right-hand contact of sequence switch spring 117, right-hand armature and front contact of relay 139 to ground, for moving sequence switch 100 out of position 17 and into position 18.

In case the call has been unsuccessful and the calling subscriber had received no answer, charge relay 152 would not have been operated. Therefore, when the calling subscriber replaced his receiver on the hook relay 139 would have been deenergized and caused sequence switch 100 to move into position 17 as previously described. In this case however, the deenergization of relay 139 would have caused the deenergization of relay 102 as soon as relay 139 deenergized, since with charge relay 152 deenergized no holding circuit for relay 102 is in existence. Sequence switch 100 would therefore have been immediately moved out of position 17 and into position 18, due to the closure of a circuit from grounded battery, power magnet of sequence switch 100, conductor 168, lower contacts of sequence switch spring 169, right-hand armature and back contact of relay 102 to ground. The release of relay 102 would also have caused the immediate release of the calling subscriber's individual line switch in a manner to be hereinafter described.

In position 18 of sequence switch 100 a circuit is completed from grounded battery, winding of down drive magnet 178, upper contacts of sequence switch spring 169, right-hand armature and back contact of relay 139 to ground. Under the control of magnet 178 the district brush shaft is restored to its normal position, and when its normal position is reached a circuit is completed from grounded battery, power magnet of sequence switch 100, lower left-hand contact of sequence switch spring 116, normal commutator segment 179, commutator brush 180, to ground, for moving sequence switch 100 out of position 18 and into position 1.

As soon as sequence switch 100 leaves position 17 the battery supply on the sleeve terminal of the line switch is cut off, and the cut-off relay of the calling line is deenergized to allow the calling subscriber's line switch to be restored to its normal position. The deenergization of relay 102 also removes the busy ground condition from the test terminal of the line switch to render the switch selectable by other hunting line switches.

The restoration of the district switch shown in Fig. 2 causes the restoration of the

succeeding switches in the train in the manner fully described in the hereinbefore mentioned Lundell application, Serial No. 487,520.

Referring now to Fig. 1 the release of the calling subscriber's individual line switch will be described. As soon as cut-off relay 3 is deenergized, stepping magnet 4 is energized in a self-interrupting circuit extending from grounded battery, winding, armature and back contact of magnet 4, lowermost armature and back contact of cut-off relay 3, right-hand armature and back contact of line relay 2, off-normal contact 13 to ground. The operation of magnet 4 causes the line switch to be advanced into its normal position, at which time contact 13 is opened to bring the switch to rest.

The manner in which the apparatus is restored to its normal condition in case the calling subscriber prematurely abandons his call, that is, replaces his receiver before the connection is completed, will now be described.

The replacing of the receiver by the calling subscriber will in every case, result in the deenergization of differential relay 139 and the consequent deenergization of relay 102 and cut-off relay 3, as just described, so that the line switch is immediately restored in every case. This immediate release of the line switch is a novel feature and will be claimed hereinafter.

It will first be assumed that the district switch has been completely positioned at the time the calling subscriber replaces his receiver. In this case the district sequence switch is in position 10.

If the sequence switch 100 had been in some position before that in which trunk-hunting takes place, the deenergization of relay 139 will complete circuits for restoring the district switch immediately. However, with the district switch positioned, in order to prevent the possibility of failure to release the succeeding switches in the train and to completely operate the sender, it is necessary to wait until all the switches have been set before the district switch can be released. Sequence switch 100 does not move out of position 10 since it cannot advance until relay 107 is deenergized, and this relay is maintained energized by means of a circuit completed at the right-hand armature and front contact of relay 152, which it will be remembered is at this time, held energized by means of ground supplied to conductor 144.

In case the subscriber had dialed his complete code at the time of replacing his receiver, all of the switches are set as previously described, and sequence switch 100 is moved out of position 10 and into position 13 as previously described. However, since the subscriber has now abandoned the call

a circuit is completed as soon as sequence switch 100 reaches position 12, this circuit extending from grounded battery, power magnet 100, conductor 168, lower right-hand and upper left-hand contacts of sequence switch spring 169, right-hand armature and back contact of relay 139, to ground, for advancing sequence switch 100 out of position 12 and into position 17.

Since relay 102 is deenergized as soon as relay 139 is deenergized, because charge relay 152 cannot reoperate under these conditions, sequence switch 100 is immediately moved out of position 17 and into position 18, due to the completion of a circuit extending from grounded battery, winding of power magnet of sequence switch 100, conductor 168, lower contacts of sequence switch spring 169, right-hand armature and back contact of relay 102, to ground. The completion of this circuit causes the advance of sequence switch 100 out of position 17 and into position 18. The district selector is then restored to its normal position as previously described.

In case the calling subscriber abandons the call without having fully dialed the digits of the wanted number, and assuming that the district switch has been positioned at the time such abandonment takes place, the release of the apparatus is accomplished in a manner substantially like that described.

As before, relay 139 is deenergized, due to the differential action of its right-hand winding when direct ground is supplied to such winding to cause the deenergization of relay. When the calling subscriber abandons the call under the conditions under discussion, the opening of the impulse circuit causes the deenergization of line relay 215 and the subsequent deenergization of slow-release relay 217. An energizing circuit for relay 220 is thereupon completed by way of the right-hand armatures and back contacts of relays 217 and 215. Relay 220 supplies ground through no resistance to conductor 144 by way of its armature and front contact and the contact of sequence switch spring 397, thus short circuiting resistance 223, and allowing sufficient current to flow through the right-hand winding of relay 139, to cause the release of this relay, due to the differential action of its windings. The deenergization of relay 139 causes the deenergization of relay 102 and cut-off relay 103, with the subsequent restoration of the line switch. The succeeding switches in the train are operated in turn, but since certain ones of the registers have not been positioned, the switches controlled by them will be caused to take 0 settings, since in the normal positions of the registers they will control the counting relays to send one pulse only in each case. When the sender sequence switch reaches position 18 the advance of the sender

125

130

circuits and the release of the district switch take place as previously described.

If the calling subscriber abandons the call before the district switch has been positioned the release of the district switch may be accomplished in one of several ways, depending upon the particular position in which sequence switch 100 is resting at the time of the abandonment of the call. In each case the replacing of the receiver causes the deenergization of relays 215 and 217. With relays 215 and 217 deenergized, relay 220 is energized as described by means of a circuit extending through the right-hand armatures and back contacts of relays 215 and 217. The energization of relay 220 causes direct ground to be supplied to conductor 144, and consequently causes the deenergization of differential relay 139. The deenergization of relay 139 causes the deenergization of relays 102 and 3 as previously described.

If sequence switch 100 has not reached position 7 at the time of the abandonment of the call, the deenergization of relay 102 completes a circuit from grounded battery, winding of power magnet of sequence switch 100, conductor 168, lower contacts of sequence switch spring 169, right-hand armature and back contact of relay 102 to ground for moving sequence switch 100 out of whatever position it is in and into position 7. In position 7 with relay 102 deenergized, a circuit is completed from grounded battery, winding of down-drive magnet 178, upper right-hand and lower left-hand contacts of sequence switch spring 169, right-hand armature and back contact of relay 102, to ground. The district selector brush shaft is then restored to its normal position, and when it reaches its normal position, a circuit is completed from grounded battery, power magnet of sequence switch 100, lower left-hand contact of sequence switch spring 116, normal commutator segment 179, and commutator brush 180, to ground, for moving sequence switch 100 out of position 7 and into position 1.

In the case just described, that is, when the district switch is not positioned at the time the call has been abandoned, the succeeding switches in the train are not operated, and the sender is restored to its normal condition.

It should be observed that while stepping relay 215 is energized a slow-to-release relay 399 is energized in parallel with slow release relay 217. If abandonment of the call takes place after sequence switch 100 has reached position $7\frac{1}{4}$ the sender sequence switch will not be restored due to the fact that relay 496 (Fig. 3) is energized over a circuit extending from grounded battery, winding of relay 496, left-hand armature and back contact of relay 399, conductor 221, sender selector brush 181 and its asso-

ciated bank contact, sequence switch spring 182, to ground. In the present case since the district sequence switch had not yet reached position 7 at the time the call was abandoned, relay 496 does not find an energizing circuit upon the release of relay 399, since the circuit of relay 496 is held open at sequence switch spring 182. The release of relay 399 therefore, completes a circuit from grounded battery, power magnet of sequence switch 400, lower contact of sequence switch spring 441, right-hand armature and back contact of relay 399, armature and back contact of relay 496, to ground, for moving the sender sequence switch out of whatever position it is in, and into position 1. The release of the register switches and the class sequence switch takes place as previously described.

If sequence switch 100 is standing in position 7 at the time the subscriber abandons the call the deenergization of relay 102 will complete the above traced circuits for causing the restoration of the switch by energizing down drive magnet 178. Sequence switch 100 is advanced into position 1, by means of the normal commutator segment, as just described. The release of the sender takes place as just described.

If the calling subscriber abandons the call after sequence switch 100 has left position 7 but before it reaches position 10, the remaining switches in the train are operated, since in this case relay 496 will be energized to prevent the release of the sender sequence switch as soon as its circuit is closed at sequence switch spring 182. If the district sequence switch is in position 8 trunk hunting is completed and the setting of the succeeding switches is then completed as previously described. If all the switches have been set release takes place in the usual manner.

From the foregoing it will be apparent that if abandonment of a call takes place before the directive operations of the district switch have been completed, the district switch and the sender will be immediately restored. If the call is abandoned at any time thereafter the selective operations of the entire train of switches take place before the apparatus is restored. It should also be noted that the release of the calling subscriber's line switch is started as soon as the call is abandoned, except in the case of a completed connection to which the called subscriber has responded, in which case the release of the calling subscriber's line switch is delayed until only the message register magnet has had an opportunity to operate to register the call.

It should also be noted that relay 139 which controls the release, is at certain times caused to deenergize under the control of circuits set up in the sender, and at

other times is caused to release under the control of circuits associated with the district selector switch.

What is claimed is:

5. 1. In a telephone exchange system, an incoming line, an outgoing line, an automatic switch for interconnecting said lines, a sending device, means to operate said sending device, means to selectively control 70
10 said switch during a portion of the operation of said sending device, a differential relay controlled in accordance with the electrical condition of said incoming line, release circuits effective upon the operation of
15 said relay at certain times to cause the immediate restoration of said switch and said sending device, and means effective upon the operation of said relay at other times to cause the release of said switch and said sending device only after the complete operation of said sending device. 80
20
2. In a controlling system, a line, a differentially wound relay, means to complete an energizing circuit through one winding 90
25 of said relay, a resistance, means to complete a circuit through another winding of said relay and said resistance without releasing said relay, means to short-circuit said resistance to cause the release of said
30 relay, said short-circuiting means being controlled in accordance with the condition of said line, and means to subsequently complete a locking circuit for said relay controlled in accordance with the condition of
35 said line independently of said other winding. 95
3. In a telephone exchange system, an automatic switch, a release relay therefor, an impulse relay, a supervisory relay, means operative at certain times to control said release relay in accordance with the condition of said impulse relay, and means operative at other times to control said release relay at contacts of said supervisory relay. 100
40
45. 4. In a telephone exchange system, an incoming line, an outgoing line, an automatic switch for interconnecting said lines, an impulse relay, registering devices, means to position said registering devices under the control of said impulse relay, a sending device, means to operate said sending device in accordance with the setting of said registering devices, means to selectively control said switch during a portion of the operation of said sending device, a supervisory relay, a release relay for said automatic switch, means operative at certain times to control said release relay in accordance with the condition of said impulse relay to cause the release of said automatic switch, and means operative at other times to control said release relay at contacts of said supervisory relay. 110
50
5. In a telephone exchange system, an incoming line, an outgoing line, an automatic 120
55 switch for interconnecting said lines, a plurality of sending devices, means to associate an idle sending device with said automatic switch, an impulse relay and a set of registering devices individual to each of said sending devices, means to position said registering devices under the control of said impulse relay by means of impulses transmitted over said incoming line, means to operate said sending device, means to selectively control said switch during a portion of the operation of said sending device, a supervisory relay associated with said switch, a release relay for said automatic switch, means operative at certain times to control said release relay in accordance with the condition of said impulse relay, and means operative at other times to control said release relay at contacts of said supervisory relay. 130
60
6. In a telephone exchange system, an incoming line, an outgoing line, an automatic switch for interconnecting said lines, a plurality of sending devices, means to associate an idle sending device with said automatic switch, an impulse relay and a set of registering devices individual to each of said sending devices, means to position said registering devices under the control of said impulse relay by means of impulses transmitted over said incoming line, means to operate said sending device, means to selectively control said switch during a portion of the operation of said sending device, a supervisory relay associated with said automatic switch, a release relay for said automatic switch, means operative at certain times to control said release relay in accordance with the condition of said impulse relay, and means operative at other times to control said release relay at contacts of said supervisory relay. 135
65
7. In a telephone exchange system, a calling subscriber's line, a plurality of selector switches, a trunking switch, means to operate said trunking switch to establish connection between said calling subscriber's line and an idle one of said selector switches, release means for said trunking switch, an electromagnetic device associated with said calling subscriber's line, means operative under certain conditions to actuate said device, means to delay the operation of said release means when a calling subscriber abandons a call under said certain conditions, and means operative 140
70

when a calling subscriber abandons a call under other conditions to render said release means immediately effective.

8. In a telephone exchange system, a calling subscriber's line, a plurality of selector switches, a trunking switch, means to operate said trunking switch to establish connection between said calling subscriber's line and an idle one of said selector switches, release means for said trunking switch, a release relay for said selector switch to control also the release of said trunking switch an electromagnetic device

associated with said calling subscriber's line, means operative under certain conditions to actuate said device, means to delay the operation of said release means when a calling subscriber abandons a call under said certain conditions, and means operative when the calling subscriber abandons the call under other conditions to render said release means immediately effective.

In witness whereof, I hereunto subscribe my name this 20th day of June, A. D. 1921.

FREDERICK J. SCUDDER.
